US0D1028870S

(12) **United States Design Patent** (10) **Patent No.:** **US D1,028,870 S**
(45) **Date of Patent:** **** May 28, 2024**

(54) **BATTERY CHARGING DEVICE**

(71) Applicant: **Weihong Ma**, Huizhou (CN)

(72) Inventor: **Weihong Ma**, Huizhou (CN)

(**) Term: **15 Years**

(21) Appl. No.: **29/924,093**

(22) Filed: **Jan. 17, 2024**

(51) **LOC (14) Cl.** **13-02**

(52) **U.S. Cl.**

USPC **D13/107**

(57) **CLAIM**

The ornamental design for a battery charging device, as shown and described.

DESCRIPTION

FIG. 1 is a front, right and top perspective view of a battery charging device, showing my new design;

FIG. 2 is a rear, left and bottom perspective view thereof;

FIG. 3 is a front perspective view thereof, shown in a disassembled condition;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines shown in the drawings illustrate portions of the battery charging device that form no part of the claimed design.
